UNITED STATES PATENT OFFICE

2,203,398

COMBINATION COUCH AND BED
CONSTRUCTION

Edwin L. Weinman, New York, N. Y.

Application April 1, 1933, Serial No. 663,914
Renewed October 17, 1939

5 Claims. (Cl. 5—111)

This invention relates to improvements in couches and bedspring constructions, particularly the type where an auxiliary bed spring is housed inside the couch underneath the seat thereof and one can be used entirely separate therefrom and one of the important objects of my improvements is, to provide a frame for a bed couch or bedspring which can be folded so compactly, that it occupies only a minimum of space when collapsed and may be made and used in different forms and combinations, ranging in width from chairs to sofas or davenports.

Further objects of my improvements are to apply some of them to several modifications of foldable bed spring structures, of collapsible types, whereby the same may be made to be combined with other furniture parts, also to provide means in folding and unfolding the legs of the collapsible bedspring structures and to secure them in erect position.

In addition to the foregoing, the improvements disclosed in this application include a type of auxiliary inner bedspring construction which forms a complete double or single bed in itself and comprises a sectional bed bottom and mattress, folding and unfolding in two or three sections, supported by folding legs and fitting when collapsed, completely within an outer structure, or it may be concealed while not in use as a bed, by seat and back cushions and arms, or any other means.

These objects and other advantages and features intended to be attained by said improvements will be more clearly conveyed, by the detailed description and the accompanying drawing, presented in this specification, of which

Fig. 1 represents a side elevation of the folding bed structure, when extended and elevated to bed position.

Fig. 2 is a side elevation of the folding bed structure when folded and collapsed and showing the uppermost section in dotted lines while in uprightly raised position.

Similar characters of reference indicate corresponding parts in the several views. It will be understood, that these improvements are not limited to the details of construction and arrangements of parts, which are illustrated in the accompanying drawing, since these improvements are capable of other embodiments and that the wording and phraseology used is for the purpose of description and explanation and not of limitation.

The couch and bed structure shown in Figures 1 and 2 has a central section, of which side rail 1

is provided with a hinge-plate 2, pivoted at point 3 to the upper ends of folding leg 4 and upright angle 5 is rigidly connected to said side rail 1 to which is pivoted at point 6 the upper end of folding leg 7 and the lower ends of both folding legs 4 and 7 are connected to members 8 and 9 and these are supported by sets of double casters on swivel bearings. These legs are being folded and unfolded by the turn of a short lever 10 pivoted at point 11 to the center of the side rail 1, the upper end of this lever being pivoted at point 12 to a link 13 connected at point 14 to leg 4 and the lower end at point 15 to a link 16 connected to leg 7; the short lever 10 is also pivoted at point 17 to one end of link 18, the other end of which is pivoted at point 19 to connecting section 20 which is hinged at point 21 to hinge-plate 2 of the central side rail 1 and also at point 22 to hinge plate 23 rigidly attached to the upper folding frame section 24. To connecting section 20 are wires attached extending crosswise to the opposite section and these wires are intersected by wire links connected to the top of the coil spring sections 25 and 26, thereby supporting the mattress, between these sections.

The upper folding section 24 is supported when unfolded near its outer end by folding legs 27 pivoted thereto at point 28, and this section is spaced apart by a U shaped cross-bar 29, said cross-bar being also connected at point 30 to one end of links 31 and 32, while the other end of link 31 is pivoted at point 33 to leg 27 and the other end of link 32 to hinge-plate 2 of the side rail of the central section.

Another folding section 34 is hinged at point 35 to the upright angle 5 to the lower end of which is riveted a cross strip 36 which is also connected to the upright angle of the opposite side rail section. This cross strip 36 is co-acting with spacing bar 37, which is also connected to the opposite side rail, thereby forming the frame structure of the central bed section. The folding section 34 is supported when outwardly extended, by folding leg 38 which is pivoted to a small bracket 39 forming part of folding section 34. A connecting link 40 pivoted to central side rail 1 at point 41 and to the angular extension 43 of leg 38 automatically folds and unfolds this leg when the folding section 34 is being folded and unfolded respectively. A wire fabric of usual type is connected to the angle iron frame of folding section 34 by helical springs and connected to coil spring section 26 supporting the part of mattress 44 resting thereon and wire fabrics are also connected by helical springs to central side rail 1

and to the frame of upper folding section 24 supporting resiliently the coil spring sections 25 and 26 and mattress 44.

- 5 When the folding bed is in collapsed position as shown in Fig. 2, and is to be opened and raised to extended and elevated position, the upper folding section 24 is lifted upwardly in line with the vertically folded connecting section 20 and engages this section which is turned outwardly 10 to horizontal position with the further outward movement of folding section 24, thereby pulling on connecting link 18, which rotates the short lever 10 upward, thereby forcing links 13 and 16, pivoted to legs 4 and 7 outwardly, swinging the 15 legs on the casters to upright position and raising the central section to elevated position. The upward and outward movement of the upper section 24, also swings automatically leg 27 and spacing bar 29 to vertical position and link 31 20 which connects both, to horizontal position, when section 24 is horizontally extended by means of link 32 which is pivoted to end of spacing bar 29 and to hinge plate 2 of the central section.

- After the upper section 24 has thus been outwardly unfolded and the central section thereby automatically raised to elevated position, the inner section 34 with the mattress section attached, is lifted with leg 38 and unfolded to horizontal position, said leg being turned to vertical position by link 40 which is pivoted at point 41 to central side rail 1 and to the angular extension 43 of leg 38.

- In converting this folding bed to collapsed position, the inner folding section 34 with an end section of mattress 44 and the folding leg 38 is folded over the central section, and the upper section 24 is lifted with the other end of mattress 44 and legs 27 and folded over the inner section 34 whereby also spacing bar 29 is folded 35 on section 24 and the legs 4 and 7 folded underneath the central section, thereby collapsing with the same.

- This folding bed, as described, can be folded in transverse sections, so it may fit inside an 40 outer couch structure which may be shorter than the full length of a bed or, if desirable, may be made the width of a chair or, two of these transverse folding bed structures may be made in single widths and both rolled into an outer couch 45 and concealed therein.

- It is to be understood, that whenever any one 50 part is shown, described and claimed, the plural may be implied, unless expressly stated otherwise, and by describing in detail herein any particular 55 form, structure, or arrangement, it is not intended to limit the foregoing improvements beyond the terms of the several claims.

- Having thus explained the nature of these improvements and described one way of constructing and using the same, although without attempting to set forth all of the forms and modifications of their construction and use, I claim:

1. In the combination of a sectional bed bottom 60 a central section supported in horizontal position by folding legs, folding sections pivoted to said central section at opposite sides thereof in up-

right and horizontal position respectively, means to raise and lock said folding legs simultaneously and elevate all of the bed bottom sections thereby to the normal height of a bed when one of the folding sections is outwardly extended in horizontal alignment with said central section and means to support both of said folding sections while unfolded to horizontal position.

2. In an article of furniture the combination of a sectional spring-bottom comprising a central 10 section supported in horizontal position by foldable supporting means, outer sections pivoted to said central section at opposite sides thereof and placed in vertical and horizontal position respectively when the sectional spring bottom is folded, 15 means to raise and lock said foldable supporting means and elevate said central section thereby to the normal height of a bed by the outward turning of one of said outer sections to horizontal alignment with said central section, and means 20 to support the outermost part of said outer sections while turned outwardly to substantially horizontal position.

3. In an article of furniture, the combination of a central section supported in horizontal position by foldable supporting means, additional sections foldably connected to said central section at opposite sides thereof, means to turn one of said sections to uprightly fixed position or to horizontal position and, means to raise said foldable supporting means and hold the same in fixed position, thereby supporting all of said sections in elevated horizontal position when one of said additional sections is outwardly extended in horizontal alignment with said central section, and 35 means to support the outermost part of said outer sections, while turned outwardly to substantially horizontal position.

4. In an article of furniture the combination of a plurality of frame members including a central frame member supported by foldable supporting means, additional frame members foldable to a fixed upright position and to a horizontal position respectively, said foldable supporting means being adapted to hold the same 40 locked in fixed position and thereby support said central frame member at the normal height of a bed, when one of the additional frame members is outwardly extended in horizontal alignment with said central frame member.

5. In an article of furniture the combination of a central section supported in horizontal position by collapsible supporting means, additional sections pivotally connected to said central section at opposite sides thereof, one of said sections being turnable to uprightly fixed position and to horizontal position, and means connected to said uprightly turnable section, to said central section, and to said collapsible supporting means, whereby the latter may be raised simultaneously 55 upward, and held in fixed position, thereby elevating said central section to the normal height of a bed, when said additional section is extended outwardly, from uprightly folded position to horizontal position.

EDWIN L. WEINMAN.
